(57) **CLAIM**

The ornamental design for a laparoscopic adaptor, as shown and described.

DESCRIPTION

FIG. 1 is a perspective view of a laparoscopic adaptor showing our new design;

FIG. 2 is a top view thereof;

FIG. 3 is a side elevation view thereof;

FIG. 4 is a bottom view thereof;

FIG. 5 is an enlarged rear view thereof; and,

FIG. 6 is an enlarged front view thereof.

The dot-dash broken lines immediately adjacent to the claim and define unshaded regions depict the bounds of the claimed design, while all other dot-dashed broken lines are directed to environment. The broken lines form no part of the claimed design.
